RICHARD W. BRONSON, OF SOUTH EUCLID, OHIO, ASSIGNOR TO THE VAN DORN IRON WORKS COMPANY, OF CLEVELAND, OHIO, A CORPORATION OF OHIO

SWING DOOR KEYLESS LOCKING DEVICE

Application filed March 8, 1932. Serial No. 597,509.

This invention relates to locking means for jail doors and more particularly to keyless locking means for remote operator control, especially applicable to swinging jail doors.

8 An object of the invention is generally to insure that a door is locked, whenever it is closed and the control mechanism is set in locked position, and to provide that whenever a door is open its control mechanism will 10 not indicate locked.

Another object is to provide novel latch means for the door.

The exact nature of this invention together with further objects and advantages thereof 15 will be apparent from the following description taken in connection with the accompanying drawings, in which Fig. 1 is a view in elevation showing a cell front wall in which an embodiment of my invention is incorporated, 20 parts being broken away to show details of construction; Fig. 2 is a detail as in the horizontal plane of line 2—2, Fig. 1, and including broken lines to indicate operation of the parts there shown; Fig. 3 is an enlarged detail in horizontal section as in the plane of line 3—3, Fig. 1; Fig. 4 is a correspondingly enlarged sectional elevation as in the plane of line 4—4, Fig. 3; Figs. 5, 6 and 7 are further enlarged sections in the same plane but 25 viewed from the opposite direction, showing the parts in different relative positions; and Fig. 8 is a section as in the plane of line 8—8, Fig. 5.

With reference now to the drawings, 1 is 30 the first door of a row of cells indicated by the cell front appearing in Fig. 1. The door is a swinging door hinged to move about the rod 2 to open outwardly from and close against a hollow pilaster 3.

40 A lock bolt 4 is mounted in the pilaster 3 for sliding movement through an opening therein to engage an opening 5 in the edge frame member 6 of the door, to lock the door in closed position, as indicated in Fig. 3.

45 Means are provided for remote operator control of said lock bolt, as from a control lever 7 at the end of the cell row. As indicated, such means comprises a bell crank 8 having one arm associated with the lock bolt 4 and 50 the other connected to a pull rod 9 extending

to an arm of a second bell crank 10, the lever 7 having connection with this second bell crank as through a cable 11 passing over a sheave 12. A spring 13 has connection with the bell crank 8 to yieldably urge the parts 55 in locking direction.

Thus, when the handle of the lever 7 is depressed the bolt 4 will be withdrawn into the pilaster 3, and upon release of the control lever the spring 13 will urge the parts in 60 the opposite direction tending to return the bolt outwardly and the lever upwardly to locked position.

Means are provided, however, for preventing movement of the lock bolt to locked position except when the door is closed and consequently in a position to be so locked by the bolt. 65

To this end I arrange a bar 14 within the pilaster for vertical sliding motion along 70 the pilaster wall adjacent the door. This bar may be mounted by means of a plurality of slots 15 each about a fixed pin 16. The bar is provided with an opening 17 to receive the bolt 4, and the mounting of the bar is such 75 that it may have a lower position wherein the lock bolt opening in the pilaster wall is masked by the bar, and an upper position wherein the openings in the bar and in the pilaster are aligned to receive the lock bolt. 80 This latter uncovering position is indicated in Figs. 1, 3, 4, 5 and 8.

The bar 14 is balanced to its lower or masking position by its own weight and preferably also by a spring 18; so that whenever 85 the lever 7 is manipulated to withdraw the lock bolt 4, the bar 14 will be released by its control mechanism to drop to masking position provided tongue 20 is partly or wholly withdrawn, masking the bolt opening in the pilaster 3 and preventing return of the bolt to locked position. The parts are so proportioned and arranged that the withdrawing stroke of the lock bolt is sufficient for this 90 purpose. 95

Means are provided for raising the bar 14 to uncover the lock bolt as the door closes. Such means include a bevel or cam surface 19 as on the bar 14, and a cooperative tongue 20 mounted on the edge of the door 1 to enter 100

an opening 21 in the pilaster as the door closes, these parts best appearing in Figs. 4-8 inclusive. Thus except when the door is fully closed and in a position to receive the lock bolt, the bar 14 will be positioned to prevent the lock bolt from projecting from the pilaster, the bar completely masking the pilaster bolt opening until the door is substantially closed.

10 That the bar 14 cannot be raised by insertion of means through the opening 21, I provide at the top of the bar means blocking its raising motion at all times except when the door is closed. For this purpose the bar 14 extends upwardly so that its upper extremity 14a projects above the pilaster when the bar is in uncovering position, and a stop bolt 22 is mounted upon the door header to block or clear the path of the end 14a of the bar, 20 and is associated with the door to be controlled thereby. A crank 23 is mounted to move concentric with the door 1, a rod 24 is arranged to connect this crank with the stop bolt 22, and a spring 25 is arranged to yieldably urge the stop bolt to a position blocking the bar 14. The rod has a lost motion connection as by the slot 26 so proportioned and arranged that the stop bolt 22 is released to the action of the spring 25 to assume blocking 25 position at all times except just as the door closes.

When the door is quickly closed by hand and immediately pulled in the opening direction, the inertia of the lock bolt 4 and its appurtenances may slow down the outward travel of the lock bolt 4 so that it enters the opening 17 in the bar 14 but its inertia does not permit it to travel sufficiently fast to reach the opening 5 in the door before the 30 door is removed from the vertical plane of the lock bolt. The lock bolt is thus permitted to move outwardly its full stroke, the lever 7 will rise to the locked position, but the door will be open. To prevent such false indication, the tongue 20 on the door is provided with a notch 30 and the bar 14 is provided with an extension 31 carrying a latch bolt 32 of very slight mass cooperative with the notch 30. The latch bolt is arranged for limited vertical sliding motion as by the slot and pin mounting means indicated at 33, and spring 34 serves to yieldably urge the latch bolt upwardly. The latch bolt has the usual bevel 35 and the parts are so proportioned 35 and arranged that when the bar 14 is in uppermost position the tongue will be engaged by the latch bolt when the door is fully closed as in Fig. 5; and when the bar 14 is in lowermost position Fig. 7, the latch bolt will be withdrawn well below the path of the tongue. If now, the door be quickly closed and immediately pulled or slammed back in the opening direction, the latch bolt 32, due to its slight inertia will engage the notch 30 before the door can be opened thus holding the

door shut and necessitating the latch bolt 4 entering the opening 5 upon completion of its stroke.

It will be appreciated that as is usual in jails, a number of cells will be arranged in a row all having similar doors, each having means for control from a common point. Thus in Fig. 1 of the drawings, a second door and its controlling mechanism is indicated, the parts pertaining to the second door bearing primed reference characters corresponding with those described in connection with the first door. The first door is indicated as locked closed and the second door unlocked and partly open.

Operation will be apparent, assuming the door closed but unlocked. Its lock bolt 4 has been withdrawn and its bar 14 is left resting upon the tongue 20 of the door. Thus, although its control lever 7 has been fully depressed to withdraw its bolt, until the door is opened upon release of the lever the latter may return to locked position by which the door would be indicated as again locked.

The door being unlocked, the bar 14 is free to rest upon the tongue 20. As the door opens, however, the tongue 20 is withdrawn allowing the bar 14 to drop to masking position. Thereafter upon release of the control lever 7 the latter will not return to its upper or locked position, so that the door will be indicated to the operator not only as unlocked but also as not closed. Also, as the door opens and immediately the bar 14 is lowered to masking position, the stop bolt 22 moves over the bar to block its return to unmask the lock bolt.

Upon reclosing of the door, if the control lever 7 be free to move, the stop bolt 22 is withdrawn, the bar 14 raised, and the bolt 4 slid into the door under the action of the spring 13, this operation causing raising of the control lever 7 to indicate that the door is locked.

Should the door be slammed closed to raise the bar 14 only instantaneously, so that the bar might otherwise be relowered before engagement by the lock bolt 4, the door will be momentarily latched in closed position by engagement of the latch bolt 32 with the tongue 20. Thus engagement of the lock bolt is insured whenever the control mechanism is set in locked position and the door is closed.

The mechanism within the pilaster is, of course, protected against tampering, by the pilaster itself. The mechanism above the doors, and that connecting with the control levers is likewise protected by the usual cover 27.

What I claim is:

1. In combination with a jail door, a lock bolt for said door, a bar arranged for movement between a position masking said bolt to prevent its entry into said door, and a po-

- sition uncovering said bolt to allow its entry into said door, said bar being balanced to said masking position, means providing for door actuation of said bar to move the latter to uncovering position as said door completes its closing movement, and latch means carried by said bar and cooperative with means on said door to secure the latter in closed position, as when the door is slammed, sufficiently long to insure engagement of the door by said lock bolt if its control has been set for locking. 70
- 5 to uncovering position as said door completes its closing movement, a stop bolt arranged to block the path of said bar to prevent movement of the latter from masking position to uncovering position, means associating said stop bolt with said door to cause withdrawal of said stop bolt from bar-blocking position only as the door closes, and means providing for operator control of said lock bolt subject to the control had by said bar. 75
- 10 2. In combination with a swinging jail door, a lock bolt for said door, means yieldably urging said lock bolt to locking position, operator-controlled means for withdrawing said bolt from said position, a bar arranged for movement between a position masking said bolt to prevent its entry into said door, and a position uncovering said bolt to allow its entry into said door, said bar being balanced to said masking position, means providing for door actuation of said bar to move the latter to uncovering position as said door completes its closing movement, a stop bolt arranged to block the path of said bar to prevent movement of the latter from masking position to uncovering position, and means associating said stop bolt with said door to cause withdrawal of said stop bolt from bar-locking position only as the door closes. 80
- 15 25 30 35 40 45 50 55 60 65 70 75 80 85 90 95 100 105 110 115 120 125 130
3. In combination with a swinging jail door arranged to close against a pilaster, a lock bolt for said door arranged in said pilaster to project through an opening therein, a bar arranged in said pilaster for movement between a position masking said opening to prevent projection of said bolt therethrough, and a position uncovering said opening, said bar being balanced to said masking position, means providing for door actuation of said bar to move the latter to uncovering position as said door completes its closing movement, said means comprising cooperative cam parts on said bar and on said door, said pilaster having an opening to allow cooperation of said cam parts, a stop bolt arranged to block the path of said bar to prevent movement of the latter from masking position to uncovering position, means associating said stop bolt with said door to cause withdrawal of said stop bolt from bar-blocking position only as the door closes, and means providing for remote operator control of said lock bolt subject to the control had by said bar. 105
4. In combination with a jail door, a lock bolt for said door, lock bolt controlling means, a bar arranged for movement between a position masking said bolt to prevent its entry into said door, and a position uncovering said bolt to allow its entry into said
